CONTROLLER FOR PRINTING PRESSES

Eric H. Laabs, Milwaukee, Wis., assignor to Cutler-Hammer, Inc., Milwaukee, Wis., a corporation of Delaware

Application June 30, 1933, Serial No. 678,440

6 Claims. (Cl. 164—43)

This invention relates to controllers for printing presses, and more particularly to controllers including means operable upon web breakage to stop the press and to sever the web at a given point.

Heretofore it has been customary to employ separate circuits under the control of a so-called "paper-break" switch for energizing elements of the stopping means and the web severing means. 10 In some instances one circuit has been supplied with alternating current and the other with direct current, whereas in other instances both circuits have been supplied with direct current with a substantial difference in voltage of the two circuits and hence it often has been necessary for 15 housing of such circuits to employ separate conduits therefor. Also employment of such separate circuits has resulted in complications where a number of press units are coordinated for different groupings necessitating commutations of 20 control circuits including the paper-break switch circuits.

The present invention has among its objects to provide an improved controller wherein wiring 25 of the paper break switch is greatly simplified as is also housing of the wires.

Another object is to so coordinate the paper-break switch, the stopping means and the web severing means as to greatly facilitate such 30 commutation or transfer of control connections as may be required for different groupings of a number of press units.

Another object is to enable both sets of the conventional form of paper-break switch to be 35 employed for controlling the two wire circuit herein proposed whereby burning of the contacts in service is greatly reduced.

Another object is to provide a controller of the aforesaid character rendering the paper-break switch operable to stop the press without 40 severing the web when the press speed is below a predetermined limit.

Other objects and advantages of the invention will hereinafter appear.

45 The accompanying drawing illustrates diagrammatically one embodiment of the invention, and the same will now be described, it being understood that the invention is susceptible of various modifications without departing from the 50 scope of the appended claims.

In the drawing,

Figure 1 shows a controller having a single paper-break switch, while

55 Fig. 2 shows coordination of a number of paper-break switches.

Referring to Fig. 1 of the drawing, the same shows an alternating current motor 1 for driving a press, such motor to be supplied with current from lines L¹, L², L³, it of course being understood that the motor may be of any preferred type, 5 and that in lieu of the single motor 1 the drive may comprise a large motor and a small motor in accordance with common practice.

The controller illustrated comprises a switch panel 2, a crosshead type controller 3 operated by a pilot motor 4 to control resistance R for motor 1 and also to control certain of the switches of panel 2 and a push button control station 5 to control the pilot motor 4, such station also being commonly employed to control certain of the 15 switches of panel 2. To avoid unnecessary complication of the disclosure of the features of the present invention the aforementioned elements of the controller and their interconnections are shown in detail only in respect of certain of the 20 commonly employed switches and circuits and of the herein proposed switches and circuits.

Thus while the switch panel 2 is ordinarily provided with numerous switches and relays for inching, running, stopping, etc., only two of such 25 switches and relays are illustrated, namely a switch 6 to control the primary circuit of the motor 1 and a "stop" relay 7 to control switch 6. As illustrated the switch 6 controls the continuity of circuit to two terminals of the motor 1, said 30 switch having an energizing winding to be connected across lines L², L³ by relay 7, said relay having an energizing circuit 8—9 to be controlled by the push button station 5. However, it is to be understood that the switch 6 may be of the 35 triple pole type to afford disconnection of all terminals of the motor and that the "stop" relay 7 may be employed to control switch 6 directly as illustrated or through another relay in accordance with common practice.

40 Switch panel 2 as shown also has thereon a relay 10 and a relay 11. Relay 10 which controls a short-circuit for the winding of the "stop" relay 7 has two windings 10^a and 10^b, the former having in circuit therewith contacts 11^a of relay 11, 45 and the latter having in circuit therewith contacts 11^b of said relay. Relay 11 has an operating winding to be connected across lines L², L³ when the crosshead driven by the pilot motor 4 bridges certain of contacts 12—13 and said relay 50 upon responding opens its normally closed contacts 11^a and closes its normally open contacts 11^b.

The controller further comprises a paper-break switch 14 having two sets of contacts 14^a and 14^b, 55

said switch being normally open, and being adapted to be closed upon breakage of the web supplied to the press, by an arm 15 which rides on the web and falls when the web breaks. As 5 illustrated the web is supplied from a roll 16 and is passed over a roll 17 to and through the press cylinders 18 and thence over rolls 19 and 20, the arm 15 resting on the web at a point between the last mentioned rolls. The paper- 10 break switch controls circuit to the contacts of relay 11 which circuit includes the operating winding 21 of a web cutter 22 shown as positioned to cut the web at a point between the roll 17 and the press cylinders. It is of course to be 15 understood that the paper-break switch and the web cutter may be of any of the well known types, and that the two sets of contacts of the paper-break switch may be connected either in series or parallel to afford multiple break of the 20 circuit controlled thereby.

Assuming the relay 11 to be energized, closure of the paper-break switch completes circuit from line L² through said switch to and through the winding 21 of the web cutter, and thence through 25 the contacts of relay 11 to and through the winding 10^b of relay 10 to line L³. Thus closure of the paper-break switch with relay 11 energized provides for operation of the cutter 22 and for operation of relay 10 by winding 30 10^b to short-circuit the winding of "stop" relay 7 to stop the press motor 1 by opening switch 6. However, the relay 11 is normally open and is energized only when the crosshead controller 3, which as will be understood is employed for speed 35 control of motor 1 is moved in a speed increasing direction to bridge contact 13 with a contact 12 connected to the winding of relay 11. Thus it will be understood that when the press is operating at a lower speed the web cutting and stopping circuit just described will be ineffective. Also it will be understood that the speed at 40 which relay 11 is energized may be varied by increasing or decreasing the number of contacts 12 connected to the winding of relay 11.

On the other hand, when the paper-break switch closes with the relay 11 deenergized said switch completes a circuit from line L² to and through the winding 21 of the web cutter, thence to and through a resistance *r*, contacts 11^a of 45 relay 11 and the winding 10^a of relay 10 to line L². The resistance *r* is of such value that the current allowed to flow in the circuit just traced is inadequate to effect operation of the web cutter, whereas the winding 10^a of relay 10 is so designed 55 as to be responsive to the reduced current of this circuit to operate relay 10 for short-circuiting the "stop" relay. Thus provision is made whereby with the relay 11 open, as it is when the press is operating below a given speed, operation of the 60 paper-break switch effects stopping of the press without operating the web cutter.

The provision for stopping the press without cutting the web when the press is operated at slow speed has been found very desirable, and 65 as aforesaid use of the paper-break switch to control only a single circuit facilitates wiring and housing of the wires and minimizes contact troubles. Also the control herein disclosed has the advantage of effecting quicker response of 70 the web severing device than is obtainable where energization of the winding of said device is in accordance with common practice dependent upon response of some instrumentality following response of the stopping means.

75 Furthermore as exemplified in Fig. 2, the cir-

cuit herein proposed has additional advantages. As shown in this figure the paper-break switch 15 may have connected in parallel therewith additional paper-break switches 15^a to control a common "stop" relay 7, the winding 21 of the web cutting device 22 being connected in the branch circuit of paper-break switch 15 and windings 21^a of additional web cutting devices being connected in the branch circuits of the additional paper-break switches. This very simple 10 multiple circuit arrangement provides for operation of the common "stop" relay upon operation of any one of the paper-break switches and for operation of the web severing devices selectively, since each of the web severing device windings 15 has only one of the paper-break switches in series therewith.

As will be apparent, the circuit herein proposed is applicable to either alternating or direct current controllers and is particularly advantageous 20 where the circuits of the paper-break switches are to be extended through transfer switches, as is frequently desired in the control of a number of press units, since the circuit herein proposed requires only two contacts per transfer 25 switch.

What I claim as new and desire to secure by Letters Patent is:

1. In a printing press controller, in combination, stopping means, web severing means, each 30 of said means having a control winding, a supply circuit for said windings including the latter in a series relation and a control switch for said circuit operable automatically upon web breakage.

2. In a printing press controller, the combination with motor control means including speed varying means and stopping means, of a web severing device, a common control element for said stopping means and said web severing device, and electrical means under the control of said motor control means to render a given operation of said element effective to cause operation of said stopping means and said web severing device or operation of said stopping means only, 45 said electrical means having circuit connections affording all necessary current supply free from variation by the electrical condition of the controlled motor.

3. In a printing press controller, the combination with motor control means including speed varying means and stopping means, of a web severing device, a common control element for said stopping means and said web severing device, said element on a given operation thereof 55 always effecting operation of said stopping means, and means operable to render said web severing device responsive or unresponsive selectively to said given operation of said element, the last mentioned means being electroresponsive and under the control of said speed varying means and having circuit connections affording all necessary current supply free from variation by the electrical condition of the controlled motor.

4. In a printing press controller, the combination with motor control means including stopping means having control windings either of which when energized effects stopping, of a circuit having parallel branches for said windings 70 with current reducing means in one branch and a web severing device having a control winding so connected in said circuit that when the latter is closed said web severing device will be unresponsive if only the branch including said cur- 75

rent reducing means is closed and will be responsive if another of said branches is closed.

5. In a printing press controller, the combination with motor control means including stopping means having control windings either of which when energized effects stopping, of a circuit having parallel branches for said windings with current reducing means in one branch, a switch operable upon breakage of the press web 10 to complete said circuit for energization of the closed branch or branches thereof, a web severing device having a control winding included in said circuit in series relation with the aforementioned branches, the last mentioned winding being unresponsive to the current traversing the branch including said current reducing means but responsive to the current traversing another of said branches whereby the last mentioned branch may be opened to provide for stopping without 15 web severing upon operation of said switch or may be closed to provide for both stopping and severing of the web.

6. In a printing press controller, the combina-

tion with motor control means including speed regulating means and stopping means, the latter having a plurality of control windings, of a switch operable upon breakage of the press web, a circuit controlled by said switch having parallel branches for said windings of said stopping means and having means to limit one of said branches to a reduced current flow, means to open or close another of said branches according to the setting of said speed regulating means, said windings providing for stopping operation of said stopping means upon operation of said switch even when the last mentioned branch is open, and a web severing device having an operating winding connected in said circuit to be subjected 10 to the current flow traversing either of said branches, said web severing device being unresponsive to the current traversing said circuit when limited to the aforesaid reduced flow and being responsive to the current traversing said 15 circuit when not so limited.
